BENJAMIN F. BOWEN, OF RICHMOND, CALIFORNIA, ASSIGNOR OF ONE-HALF TO H. W. BOTTGER, OF RICHMOND, CALIFORNIA

ROTARY VALVE

Application filed August 9, 1928. Serial No. 298,534.

My invention relates to improvements in valves for internal combustion motors wherein conical rotary valves operate in conjunction with means actuated by the motor for alternately connecting and disconnecting each cylinder of the motor with its intake and exhaust ports respectively and in synchronism with the cycles of the pistons mounted within the cylinders of said motor.

10 The primary object of the present invention is to provide a new and improved valve for internal combustion motors;

Another object of the present invention is to provide a new and improved conical 15 rotary valve which will alternately connect and disconnect a cylinder of an internal combustion motor with its intake and exhaust ports in synchronism with the cycles of the piston of the motor;

20 A further object of the present invention is to provide a new and improved conical rotary valve provided with means for normally holding said valve onto its seat whereby rotation of said valve will continuously 25 grind a new seat and thereby insure perfect sealing of the cylinder during the compression and power strokes;

A still further object is to provide a rotating valve stem loosely connected longitudinally to the valve to prevent unseating 30 of said valve.

I accomplish these and other objects by means of the preferred form of the device disclosed in the drawings forming a part 35 of the present application wherein like characters of reference are used to designate similar parts throughout the specification and drawings, and in which—

40 Fig. 1 is a broken transverse sectional view of an internal combustion motor, disclosing my improved valve applied thereto;

Fig. 2 is a sectional view taken on line 2—2 of Fig. 1 in the direction indicated;

45 Fig. 3 is a broken detailed view of the valve operating mechanism;

Fig. 4 is a broken detailed view, partly in section, disclosing the manner in which the valve stem is loosely connected longitudinally to the valve; and

Fig. 5 is a bottom plan view of one of the valves.

Referring to the drawings, the numeral 1 is used to designate the motor block of an internal combustion motor having the usual cylinder 2 with pistons 3 slidably mounted therein, said cylinders being connected in the usual manner by means of connecting rods 4 to the crank shaft 6. The block 1 is also provided with the usual intake and exhaust ports I and E, respectively, and between the upper end of each cylinder and its respective intake and exhaust ports I and E, respectively, I have provided a conical valve seat 7 and within each valve seat 7 is rotatably mounted a conical valve 8 having a curved channel 9 therein arranged in one position of the valve to connect the adjacent cylinder with its intake port, in a second position to disconnect said cylinder from the intake and connect it to the exhaust port, and in a third position to disconnect said cylinder from both ports, as during the compression and firing or power stroke of the piston 3, and as disclosed in these several positions in Fig. 2 of the drawings.

In order to normally retain the conical valve 8 in close contact with its conical seat 7 I have provided for each valve 8 a suitable spring 11 resting upon the top of each valve 8 and held in position and in tension by a suitable valve cap 12, which cap also closes the upper end of the valve seat 7. The lower end of the springs 11 rest upon suitable anti-friction members designated by the numeral 14.

The lower end of each valve 8 is provided with a recess 16 of irregular shape into which is longitudinally and slidably mounted the upper end of a valve stem 17 of a corresponding shape to fit into the irregular recess 16 on the lower end of the valve 8, the purpose of which is to prevent unseating of the said valve 8.

The lower end of each valve stem 17 is provided with a suitable gear 18 meshing with similar gears 19 mounted upon a counter-shaft 21 in turn rotatably mounted with-

in suitable bearings, preferably within the crank case 23 of the motor.

One end of the counter-shaft 21 is provided with a spur gear 24 meshing with a second spur gear 26, the said gears being of the proper ratio to actuate the valves 8 in synchronism with the cycles of the pistons 3 within the cylinders 2.

In operation, the vertical reciprocation of the pistons 3 within the cylinders 2 operates the crank shaft 6 in the usual manner, which crank shaft 6 by means of the gear 26 rotates the spur gear 24 of the counter shaft 21 and consequently the gears 19 thereon which gears 19 rotate the gears 18 on the valve stems 17. As the valve stems are loosely connected longitudinally, to the conical rotary valves 8 within the conical valve seats 7, said valves 8 and their respective channels 9 therein are rotated to cause said channel 9 to alternate connect and disconnect the cylinders 2 with their respective intake and exhaust ports respectively and also to disconnect both intake and exhaust ports from their respective cylinders in synchronism with the cycles of the pistons 3 within the cylinders 2.

The springs 11, cooperating with the anti-friction bearings indicated as at 14, tend to normally retain the conical rotary valves 8 within their respective conical seats 7 to seal the cylinders 2 from their respective intake and exhaust ports during the compression and power strokes. The tension of the springs 11 also serves to maintain contact of the conical valves 8 with their respective conical seats 7 whereby continued rotation of said valves within said seats will operate to constantly grind said valves and seats and thereby at all times preserve accurate contact of said valves with said seats.

As hereinbefore described the loose connections, longitudinally, of the valve stems 17 with their respective valves 8 operate to rotate said valves 8 without unseating the same for the reason that said valves 8 are free to move longitudinally in respect to said stems 17 but at the same time said valves are rotated by the engagement of the irregular end of the stems 17 with the corresponding irregular recesses in the lower ends of said valves 8. The irregular ends and recesses also serve to prevent inaccurate replacement or connection of the valves with their respective stems.

Having thus described my invention what I claim as new and desire to secure by Letters Patent is—

1. The combination with the cylinder block and head of an internal combustion engine having intake and exhaust passages adapted to communicate with each cylinder of the engine and having a conical valve seat formed between the intake and exhaust passage for each cylinder, of a conical valve

rotatably seated within each valve seat and having a channel arranged to alternately connect and disconnect the exhaust and intake passages with the cylinder; caps mounted upon the block to normally close openings formed over each valve, and removable to permit the inserting and removal of said valves through said openings; means mounted between the caps and the valves to normally hold the valves seated; valve shafts rotatably mounted upon the block and having their upper ends engaging the valves to rotate the same, said valves being slidably movable axially relative to the shafts to compensate for wear and to permit removal of the valves from said shafts; and means for rotating the shafts to actuate the valves in timed relation to the movement of pistons mounted within the cylinders.

2. A rotary valve for internal combustion engines comprising a conical valve seat formed between intake and exhaust passages adapted to communicate with a cylinder of an engine; a valve shaft mounted in axial alignment with the valve seat and actuated by the engine in timed relation to the operation of a piston within said cylinder; a conical valve seated within the valve seat and having a channel arranged to alternately connect and disconnect the exhaust and intake passages with the cylinder, said valve being movable axially through an opening above the valve seat to detachably engage the end of the shaft for rotation therewith and being slidably movable axially thereon to compensate for wear and to permit removal of the valve independently of the shaft.

3. A rotary valve for internal combustion engines comprising a conical valve seat formed between intake and exhaust passages adapted to communicate with a cylinder of an engine; a valve shaft mounted in axial alignment with the valve seat and actuated by the engine in timed relation to the operation of a piston within said cylinder; a conical valve seated within the valve seat and having a channel arranged to alternately connect and disconnect the exhaust and intake passages with the cylinder, said valve being movable axially through an opening above the valve seat to detachably engage the end of the shaft for rotation therewith and being slidably movable axially thereon to compensate for wear and to permit removal of the valve independently of the shaft; and means normally holding the valve seated upon its seat and in engagement with the shaft.

4. A rotary valve for internal combustion engines comprising a conical valve seat formed between intake and exhaust passages adapted to communicate with a cylinder of an engine; a valve shaft mounted in axial alignment with the valve seat and actuated

by the engine in timed relation to the operation of a piston within said cylinder; a conical valve seated within the valve seat and having a channel arranged to alternately connect and disconnect the exhaust and intake passages with the cylinder, said valve being movable axially through an opening above the valve seat to detachably engage the end of the shaft for rotation therewith and being slidably movable axially thereon to compensate for wear and to permit removal of the valve independently of the shaft; a cap mounted to normally close the opening above the valve; and a spring compressed between said cap and the valve to normally hold said valve seated and in engagement with the shaft.

5. A rotary valve for internal combustion engines comprising a conical valve seat 20 formed between intake and exhaust passages communicating with a cylinder of an engine; a valve shaft mounted in axial alignment with the valve seat, one end of said shaft extending into the small end of the 25 seat; means connecting the opposite end of the shaft to driving mechanism actuated by the engines to rotate said shaft in timed relation to the operation of a piston within the cylinder; a conical valve member movable axially onto the valve seat from the large end thereof through an opening aligned with said seat, the small end of said valve member slidably and detachably engaging the adjacent end of the valve shaft 30 to permit said valve member to be inserted and removed independently of the shaft, and said member having a channel to alternately connect and disconnect the exhaust and intake passages with the cylinder; a 35 cap mounted to close the opening; and a spring compressed between the cap and the valve to normally hold the valve seated and moving said valve member axially relative to the shaft to compensate for wear.

40 45 In witness whereof, I hereunto set my signature.

BENJAMIN F. BOWEN.
